(57) **CLAIM**

The ornamental design for a tire rim, as shown and described.

DESCRIPTION

FIG. 1: is a side perspective view of the tyre rim showing my new design;

FIG. 2: is a bottom plan view thereof (one side view being a mirror image);

FIG. 3: is a top plan view thereof;

FIG. 4: is a front elevation view thereof;

FIG. 5: is a side view thereof;

FIG. 6: is a side perspective view of a second embodiment of the tyre rim of FIG. 1, whereas four holes are provided for fastening bolts;

FIG. 7: is a bottom plan view thereof (one side view being a mirror image);

FIG. 8: is a top plan view thereof;

FIG. 9: is a front elevation view thereof; and,

FIG. 10: is a side elevation view thereof.
